TELEPHONE INSTRUMENT

Arthur Turnbull, Jr., Far Hills, and Herbert R. Warnke, East Orange, N. J., assignors to United States Instrument Corporation, East Orange, N. J., a corporation of New Jersey

Application December 4, 1937, Serial No. 178,150

9 Claims. (CL 179—119)

This invention relates to telephone instruments and more particularly to instruments of the electro-magnetic type which are adapted to be used either as transmitters or receivers. Instruments of this type are adapted to be used in circuits which do not or need not include a source of electric energy other than the instrument which, at any given moment, is serving as the transmitter, and such instruments are therefore known as "sound-powered" telephone instruments.

Heretofore, instruments of the type referred to have been relatively fragile in construction, and delicate in that they have been rather easily thrown out of adjustment by shocks due to rough handling or other causes. One object of the present invention is to provide an instrument of the class described which shall be rugged in construction and capable of withstanding severe shocks without injury and without requiring readjustment of the parts.

A second object is the provision of such an instrument which shall be unusually compact, with the attendant advantages of such a construction.

Another object is the provision of an instrument of the class described which shall be extremely efficient, the energy losses in the instrument being reduced by reason of the manner in which the instrument is constructed and assembled.

A further object of the present invention is the provision of an instrument of the class described in which the permanent magnets are arranged in such manner as to permit of conveniently magnetizing them in place, thus promoting ease of assembly and permitting the use of substantially smaller magnets, as will be hereinafter explained.

A further object is the provision of an instrument comprising permanent magnets, opposed pole-pieces, and an armature extending between the pole-pieces and being permanently adjusted in proper spaced relationship thereto.

A further object is the provision of a modified form in which the armature is mounted in such a manner as to promote ease and accuracy of adjustment when such adjustment becomes desirable.

Another object is the provision of an instrument of the class described in which the vibratory armature is adjustably secured at its respective ends, and is coupled to the diaphragm at its midpoint.

A further object is the provision of an instrument of the class described, in which the arma-

ture is supported at a point between its ends, so that both ends of the armature may vibrate in response to movements of the diaphragm.

Another object is the provision of an instrument in which the usual coil is replaced by a relatively few turns of insulated wire wound directly upon the armature itself, and adapted to vibrate therewith, without substantially reducing the responsiveness of the armature.

10 Another object is the provision of a telephone instrument of the class described, mounted upon a backing plate in such a manner that the instrument may be supported within a casing, by clamping the casing members against a peripheral flange on the backing plate, no pressure being applied to the periphery of the diaphragm, as is the usual case.

Other and further objects, features and advantages will be apparent upon a consideration of 20 the following specification taken in connection with the accompanying drawings, in which

Figure 1 is a rear elevation, partly in section, of one form of telephone instrument constructed in accordance with the present invention;

25 Figure 2 is a transverse vertical section on line 2—2 of Figure 1;

Figure 3 is a bottom view of the instrument of Figure 1;

30 Figure 4 is a top view of the instrument of Figures 1, 2 and 3, partly in section on line 4—4 of Figure 2;

Figure 5 is a fragmentary transverse section illustrating a modified form of armature mounting;

35 Figure 6 is a fragmentary section on line 6—6 of Figure 5;

Figure 7 is a bottom view of the device of Figures 5 and 6;

Figure 8 is a rear elevation of a modified form 40 of instrument employing an armature supported at a point intermediate its ends;

Figure 9 is a central transverse vertical sectional view of the instrument of Figure 8;

Figure 10 is a schematic view of a modified 45 form of instrument in which the coil is wound upon the armature;

Figure 11 is a rear elevation of a further modified form of instrument in which the armature is adjustably mounted at its respective ends and is coupled to the diaphragm at its midpoint;

Figure 12 is a central transverse vertical section of the instrument of Figure 11; and

50 Figure 13 is a horizontal section on line a—a of Figure 11.

55 In order to facilitate an understanding of the

invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

Referring first to the device of Figures 1 to 4, inclusive, it will be seen that the usual diaphragm 15 is secured to the forward face of a backing plate 16 by means of a clamping ring 17 secured by screws, annular cushioning gaskets 18 and 19 being preferably interposed between the diaphragm and the backing plate and clamping ring, respectively. The backing plate is provided with a peripheral flange 20 which projects radially beyond the periphery of the diaphragm 15, to provide for clamping the instrument in a casting. The latter comprises a cup member 21 and a cover member 22, having threaded engagement with each other, and being provided with opposed shoulders for gripping the peripheral flange 20 of the backing plate therebetween. The backing plate 16 is cut away as at 23 in order to lighten the instrument as well as to provide clearance for the coupling means extending between the diaphragm and armature.

In the instrument of the present invention the usual semi-circular or horse-shoe shaped magnets are replaced by straight bar magnets, preferably substantially rectangular in cross section, and which are preferably formed of magnetic material of very high coercive force, the preferred material being an alloy of aluminum, nickel and iron commercially known as aluminum-nickel magnet alloy. It has been determined that if magnets of this material are employed, and are highly magnetized, the magnets may be made much smaller than has heretofore been the case, and may be disposed longitudinally between the usual opposed pole-pieces, thus serving as spacing members for the pole-pieces and permitting of a construction possessing great rigidity and ruggedness. Also, by disposing the magnets in the manner described, the magnetic losses are considerably reduced.

Referring to Figure 1, there are provided a pair of magnets 24 and 24' of substantially rectangular form, disposed longitudinally between the opposed pole-pieces 25 and 25' (Figures 1 and 2), the magnets serving to space the pole-pieces so as to provide a suitable gap between the adjacent portions of the respective pole-pieces for the introduction of the usual armature. The pole-pieces and magnets are maintained in assembled relation and are firmly secured to the backing plate 16 by means of bolts 26, the upper and lower surfaces of the respective magnets being provided with grooves for the reception of the bolts, thus enhancing the ruggedness and rigidity of the construction. During the assembly of the magnets and pole-pieces, the usual coil 27 is disposed between the pole-pieces, inwardly of the magnets as illustrated. An armature 28 is disposed vertically, extending through the core of the coil 27 and between the adjacent tips of the pole-pieces 25 and 25', the upper end of the armature being coupled to the diaphragm by means of a rod 29. The latter is threaded at each end and is adjustably secured to the diaphragm and the armature, respectively, by means of nuts or otherwise, the initial adjustment being such that the adjacent end of the armature is

spaced centrally in the gap between the upper tips of the respective pole-pieces. At its lower end the armature 28 is secured, by screws or other suitable means, to a downwardly extending projection 30 of a bridge 31, which is adjustably mounted upon the lower faces of the respective pole-pieces in a manner now to be described.

The bridge 31 may be formed as illustrated in Figure 3, a portion of the material being struck downwardly to form the projection 30, leaving the bridge in the form of a bifurcated member. The bifurcated end of the bridge is secured to the adjacent pole-piece by means of screws, one or more gaskets 32 being interposed between the bridge and the pole-piece in order to provide a fulcrum for rocking adjustment of the bridge. The opposite end of the latter is adjustably secured to the pole-piece 25' by means of screws 33 and 33' which are journaled in the bridge and threaded into the pole-piece 25'. An intermediate adjusting screw 34 is threaded in the bridge between the screws 33 and 33' and has its inner end in engagement with the adjacent face of the pole-piece 25'. The angular position of the bridge 31, and hence the position of the armature 28, may be regulated by adjusting the screws 33 and 33' in one direction and the screw 34 in the opposite direction.

A member 35 of insulating material is secured to the upper surface of the pole-piece 25' and provides a support for the terminals 36 and 37, which may be secured thereto in any suitable fashion, it being the intention that the respective ends of the wire constituting the coil 27 shall be connected, as by solder, to the respective terminals 36 and 37, by means of which they are similarly connected to the respective leads of the telephone circuit (not shown).

From the foregoing description it will be apparent that the present invention provides a telephone instrument of the class described which is exceedingly compact, efficient and rugged. It will likewise be appreciated that the instrument is capable of very delicate adjustments, which adjustments are more or less permanent, due to the fact that the armature mounting is of such a nature as not to be easily displaced or thrown out of adjustment.

In practice it is preferred to make the magnets 24 and 24' of the material specified above, while the pole-pieces 25 and 25' and armature 28 are made of a high grade silicon steel. The diaphragm is preferably duralumin, while the backing plate 16 and bridge 31 are preferably of brass or other non-magnetic material. Likewise, the rod 29 and the several screws and nuts are formed of any suitable non-magnetic material, preference being given to materials which are light in weight, yet possess the necessary strength. Thus aluminum and Bakelite are among the more suitable materials. The coil 27 may consist of about 1000 turns of from No. 37 to No. 40 AWG copper wire. The core is preferably of Bakelite or similar material, but may be of any suitable non-conducting and non-magnetic material.

It will be readily appreciated that because of the relative location and disposition of the magnets 24, 24' and pole-pieces 25, 25', the present construction lends itself admirably to a mode of assembly in which the core, pole-pieces and magnets are assembled, after which a magnetizing force is applied, through suitable instrumentalities, to magnetize the permanent magnets 24 and 24'. It will be readily appreciated that ease of

assembly is thus promoted, since it is much more convenient, in assembling the elements, to deal with unmagnetized members.

A more important advantage of magnetization after assembly resides in elimination of the loss in magnetization incurred in breaking the magnetic circuit, which loss is unavoidable when the magnetization is carried out prior to assembly of the device. This loss amounts to thirty per cent, more or less, of the total magnetic force of the magnets, and it is therefore apparent that by devising a structure in which the permanent magnets may be magnetized after assembly, the applicants are enabled to reduce the size of the magnets by approximately thirty per cent.

Figures 5, 6 and 7 illustrate a modification of the instrument including a form of mounting for the armature in which the latter is permanently secured in accurately spaced relationship between the lower tips of the respective pole-pieces. In this form of the invention, the armature 40 may be coupled to the diaphragm 41 in the manner previously described. The lower end of the armature is secured in an aperture 42 provided for that purpose in a bridge 42', by means of tight-fitting insulating spacers 43 and 44. The width of the aperture 42 is made to correspond with the gap between the lower tips of the respective pole-pieces, and the spacers 43 and 44, together with the armature 40, completely fill this gap, thus centering the armature permanently therein. Preferably the non-magnetic spacers 43 and 44 and the armature 40 are permanently affixed to the bridge 42' as by solder, and it is obvious that the spacers 43 and 44 may, if desired, be comprised of a single strip of material folded over the end of the armature 40 before the latter is inserted between the pole tips. It will be appreciated that in this form of device only the upper end of the armature 40 is permitted to vibrate. In effecting the initial adjustment of the upper end of the armature within the gap between the upper pole tips, the bridge and armature may be adjusted by placing shims between the bridge 42' and the lower surfaces of the respective pole-pieces.

Preferably the bridge 42' is provided with upturned projections 45 and 46 (Figure 6) for engagement in suitable sockets provided in the lower face of the coil core 47, facilitating assembly and enhancing the rigidity of the structure.

In the device illustrated in Figures 8 and 9, the magnets 50 and 50' serve to space the pole-pieces 51, 51', 52, 52', as in the case of the previous constructions, and the armature 53 is coupled to the diaphragm 54 in the manner previously described. In the present construction it is preferable to employ a pair of pole-pieces for each magnet, and the pole-pieces are of somewhat different form from those of previously described constructions. For example, referring to Figure 9, it will be noted that the pole-piece 51 has an inwardly projecting horizontal portion 55 which serves as a supporting member for the armature bridge to be later described, and an inturned pole tip 56. The opposed pole-piece 51' is formed in a similar but opposite manner so as to complement the pole-piece 51 in forming a support for the armature bridge and an air gap for the reception of the armature 53. The pole-pieces 51 and 51' extend laterally to the center of the armature, and a similar pair of pole-pieces 52 and 52' are provided therebeyond, for cooperation with the magnet 50.

In this construction the armature bridge comprises a pair of non-magnetic bridge members 57, 57' disposed above the lower pole tips of the respective pole-pieces and secured to the inwardly extending horizontal projections of the respective pairs of opposed pole-pieces as by means of screws. Thus these bridge members are disposed between the lower end of the coil 58 and the upper edges of the respective lower pole tips. The armature 53 is received between the adjacent edges of the bridge members 57 and 57' respectively, the latter being provided, for this purpose, with slots 59, 59' (Fig. 8) substantially corresponding to the thickness of the armature. Preferably the armature is secured to the respective bridge members by soldering.

By the described construction both ends of the armature are permitted to vibrate within their respective air gaps, thus considerably increasing the sensitivity of the instrument, and giving it an improved voice frequency response. Since the armature bridge is positioned below the coil, it is not necessary to increase the internal diameter of the coil core, or to decrease the effectiveness of the coil in any manner.

Figure 10 illustrates a modification which may be applied to any of the previously described constructions. In this case, the armature 60 may be coupled to the diaphragm in the manner previously described, and may also be secured at its lower end in any suitable manner, as for example, in the manner illustrated in Figure 5. The usual coil, such as the coil 27 of Figure 1, or the coil 58 of Figure 9, is omitted, and the armature 60 itself is provided with a coil 61, having a much smaller number of turns than the coils 27 and 58. For example, the coil 61 may comprise approximately 100 turns of No. 38 to No. 40 AWG wire. The coil is roughly conical in shape, the greatest concentration of turns occurring nearest the lower end of the armature, which is rigidly secured. By this expedient, the natural vibration period of the armature is not substantially affected by placing the turns directly upon the armature, and the sensitivity of the instrument is therefore not impaired. On the other hand, by reason of the coil 61 being wound directly upon the armature 60, the efficiency of the instrument is greatly increased for reasons which will be obvious. Due to the lower number of turns, the generated voltage will be correspondingly low, but may be increased by the use of a step-up transformer 62, if desired, the secondary coil of the latter being connected in the telephone circuit. If desired, the armature 60 may be supported in a manner described in connection with Figures 8 and 9 and illustrated therein.

Figures 11-13 illustrate a further modified form of instrument employing a single magnet of increased size, two coils, and an armature secured at both ends and having its midpoint coupled to the diaphragm. In this construction, as in the previous constructions, the magnet 70 serves to space the pole-pieces 71 and 71', the latter being spaced at their upper ends by sleeves 72. The pole-pieces 71 and 71' are provided with inwardly projecting U-shaped pole-tip members 73 and 73' respectively, secured thereto by welding or in any suitable fashion, there being four pole tips associated with each pole-piece, thus constituting four air gaps in all. Coils 74 and 75 are disposed in the usual manner within the spaces circumscribed by the respective opposed pairs of pole tips, and are connected in the telephone circuit in the usual manner. The armature 76 is pref-

erably longer and thinner than those employed in the previously described constructions, and is coupled to the diaphragm (not shown) in the usual manner, except that in this case the armature 76 has its midpoint, rather than one of its ends, coupled to the diaphragm. Each end of the armature 76 is adjustably mounted by means now to be described. Since the respective ends of the armature are similarly mounted, only one mounting will be described.

Referring to Figure 13, an end of the armature 76 is secured between an armature adjusting block 77 and an armature plate 78 by means of screws 79, 79', the latter being journaled in the block 77 and plate 78, and being threaded into the backing plate 80. The end of the adjusting block 77 adjacent the backing plate 80 is provided with an integral projection 81 for engagement with the surface of the backing plate 80 to serve as a fulcrum. It will be apparent that the block 77 may be rocked laterally about the fulcrum 81 by loosening one of the screws 79 and 79' and tightening the other screw, the projection 81 of the block 77 being at all times maintained in engagement with the backing plate 80. It will be understood that by rocking the respective adjusting blocks 77 the armature 76 may be suitably adjusted within the several air gaps.

By the use of an unusually long and thin armature, in the construction just described, it will be understood that the instrument is rendered considerably more sensitive, and is also more efficient by reason of the reduction of eddy-current losses in the armature and pole-pieces. Also, since the armature is mounted at both ends, the device has increased structural stability.

The modification just described may be extended to a device in which the armature may have, instead of the two arms illustrated, a greater number of arms, each vibrating within its own coil and air gaps, all of the arms of the armature being, of course, in the same plane, and extending radially from the point of connection between the armature and the diaphragm. In such a device the outer end of each arm of the armature is preferably mounted adjustably in the manner described.

It will be apparent to those skilled in the art that certain of the features above described are interchangeable between the various forms and modifications embraced in the present invention.

Having thus described the invention, what is claimed as new and desired to be secured by Letters Patent is:

1. In a telephone instrument, a pair of opposed pole-pieces having inwardly projecting pole-tips defining an air-gap between said pole-pieces, permanent magnets disposed lengthwise between and spacing said pole-pieces and serving to fix said air-gap, connecting means extending between said pole pieces and engaging said magnets for maintaining the latter in place between said pole pieces, a non-magnetic bridge member spanning the space between said pole-pieces, a vibratory armature supported on said bridge and extending between said pole-tips, a diaphragm connected to said armature, and a coil surrounding said armature and adapted to be connected in a telephone circuit.

2. In a telephone instrument, a pair of opposed pole-pieces having inwardly projecting pole-tips defining an air-gap between said pole-pieces, permanent magnets disposed lengthwise between and spacing said pole-pieces and serving to fix said air-gap, a non-magnetic bridge member spanning

the space between said pole-pieces, a vibratory armature supported on said bridge and extending between said pole-tips, a diaphragm connected to said armature, and a coil surrounding said armature and adapted to be connected in a telephone circuit, said coil being supported on and insulated from said armature.

3. In a telephone instrument, a magnetic circuit comprising a permanent magnet and opposing pole-pieces, a vibratory armature supported between said pole-pieces, a diaphragm connected to said armature, and a coil surrounding said armature and adapted to be connected in a telephone circuit, said coil being supported on and insulated from said armature and being of decreasing radial thickness toward the point of connection of said armature to said diaphragm.

4. In a telephone instrument, a pair of opposed pole-pieces having inwardly projecting pole-tips defining an air gap between said pole-pieces, permanent magnets disposed lengthwise between and spacing said pole-pieces and serving to fix said air gap, connecting means extending between said pole pieces and engaging said magnets for main-

20 taining the latter in place between said pole pieces, a non-magnetic bridge member spanning the space between said pole-pieces, a vibratory armature supported on said bridge and extending between said pole-tips, a diaphragm connected to said armature, and a coil surrounding said armature and adapted to be connected in a telephone circuit, said armature being spaced between said pole-pieces by means of non-magnetic spacing members disposed between the end of said armature 25 supported on said bridge and the adjacent ends of said respective pole-pieces.

5. In a telephone instrument, a pair of opposed pole-pieces having inwardly projecting pole-tips defining an air gap between said pole pieces, permanent magnets disposed lengthwise between and spacing said pole-pieces and serving to fix said air gap, connecting means extending between said pole pieces and engaging said magnets for main-

30 taining the latter in place between said pole pieces, a non-magnetic bridge member spanning the space between said pole-pieces, a vibratory armature supported on said bridge and extending between said pole-tips, a diaphragm connected to said armature, and a coil surrounding said armature and adapted to be connected in a telephone circuit, said armature being spaced between said pole-pieces by means of non-magnetic spacing members disposed between the end of said armature 35 supported on said bridge and the adjacent ends of said respective pole-pieces.

40 6. In a telephone instrument, a pair of opposed pole-pieces having inwardly projecting pole-tips defining an air gap between said pole pieces, permanent magnets disposed lengthwise between and spacing said pole-pieces and serving to fix said air gap, connecting means extending between said pole pieces and engaging said magnets for main-

45 taining the latter in place between said pole pieces, a non-magnetic bridge member spanning the space between said pole-pieces, a vibratory armature supported on said bridge and extending between said pole-tips, a diaphragm connected to said armature, and a coil surrounding said armature and adapted to be connected in a telephone circuit, said armature being spaced between said pole-pieces by means of non-magnetic spacing members disposed and filling the space between the end of said armature supported on said bridge and the adjacent ends of said respective pole-pieces.

50 7. In a telephone instrument, a pair of opposed pole-pieces having inwardly projecting pole-tips defining an air gap between said pole-pieces, permanent magnets disposed lengthwise between and spacing said pole-pieces and serving to fix said air gap, a non-magnetic bridge member spanning the space between said pole-pieces, a vibratory armature supported on said bridge and extending between said pole-tips, a diaphragm connected to said armature, and a coil surrounding said armature and adapted to be connected in a telephone circuit, said bridge member being mounted for rocking movement relative to said pole-pieces.

55 8. In a telephone instrument, a pair of opposed pole-pieces having inwardly projecting pole-tips defining an air gap between said pole-pieces, permanent magnets disposed lengthwise between and spacing said pole-pieces and serving to fix said air gap, a non-magnetic bridge member spanning

60 9. In a telephone instrument, a pair of opposed pole-pieces having inwardly projecting pole-tips defining an air gap between said pole-pieces, permanent magnets disposed lengthwise between and spacing said pole-pieces and serving to fix said air gap, a non-magnetic bridge member spanning the space between said pole-pieces, a vibratory armature supported on said bridge and extending between said pole-tips, a diaphragm connected to said armature, and a coil surrounding said armature and adapted to be connected in a telephone circuit, said bridge member being mounted for rocking movement relative to said pole-pieces.

65 10. In a telephone instrument, a pair of opposed pole-pieces having inwardly projecting pole-tips defining an air gap between said pole-pieces, permanent magnets disposed lengthwise between and spacing said pole-pieces and serving to fix said air gap, a non-magnetic bridge member spanning

70 11. In a telephone instrument, a pair of opposed pole-pieces having inwardly projecting pole-tips defining an air gap between said pole-pieces, permanent magnets disposed lengthwise between and spacing said pole-pieces and serving to fix said air gap, a non-magnetic bridge member spanning

75 12. In a telephone instrument, a pair of opposed pole-pieces having inwardly projecting pole-tips defining an air gap between said pole-pieces, permanent magnets disposed lengthwise between and spacing said pole-pieces and serving to fix said air gap, a non-magnetic bridge member spanning

the space between said pole-pieces, a vibratory armature supported on said bridge and extending between said pole-tips, a diaphragm connected to said armature, and a coil surrounding said armature and adapted to be connected in a telephone circuit, said bridge member being disposed adjacent one end of said coil and inwardly of the adjacent pole-tips, and providing a pivotal support for said armature.

8. In a telephone instrument, a telephone motor including spaced pole-pieces having inwardly projecting pole-tips, a coil, and an armature extending between said pole-pieces, a bridge member spanning the space between said pole-pieces and disposed between one end of said coil and the adjacent pole-tips and providing a pivotal support for said armature, said bridge member being disposed closely adjacent said last mentioned

pole-tips and said coil extending into relatively close relation to said bridge member.

9. In a telephone instrument, a telephone motor including a pair of opposed pole-pieces having inwardly projecting pole-tips defining an air gap between said pole-pieces, permanent magnets disposed lengthwise between and spacing the respective pole-pieces of said pair and serving to fix said air gap, connecting means extending between said pole-pieces for maintaining said magnets in place between said pole-pieces, an armature extending between said pole-tips, means supporting said armature for vibratory movement, a diaphragm, and means connecting said diaphragm and said armature.

ARTHUR TURNBULL, JR.
HERBERT R. WARNE.
